United States Patent

Des. 237,727
Patented Nov. 18, 1975

237,727

AMUSEMENT GAME TABLE

Robert Ralph Runte, Buffalo Grove, Ill., assignor to Fascination, Ltd., Des Plaines, Ill.

Filed July 29, 1974, Ser. No. 492,529

Term of patent 14 years

Int. Cl. D21—01

U.S. Cl. D34—5 J

FIG.1

FIG.3

FIG. 1 is a perspective view of an upper portion and side of the amusement game table, showing the new design;

FIG. 2 is a top view of the amusement game table shown in FIG. 1; and

FIG. 3 is a right-side elevational view of the amusement game table thereof, the left side being substantially similar.

I claim:

The ornamental design for amusement game table, substantially as shown and described.
